FURNACE REGENERATOR SYSTEM

William J. Irwin, Wilkinsburg, Pa.

Application March 1, 1938, Serial No. 193,357

5 Claims. (Cl. 263—19)

This invention relates to furnace regenerators and is intended to effect a more uniform flow of the products of combustion through the same, particularly in those instances where a plurality of regenerators work in parallel at one end of a furnace.

A specific example of the invention as applied to an open-hearth metallurgical furnace is illustrated by the accompanying drawing, in which: 10 Figure 1 is a longitudinal vertical section of the furnace;

Figure 2 is a horizontal section through the regenerators and the flues extending from the same to the furnace and the stack;

15 Figure 3 is a longitudinal vertical section taken from the line III—III in Figure 2; and

Figure 4 is a transverse vertical section taken from the line IV—IV in Figure 2.

Since the regenerators are similarly arranged 20 at opposite ends of the furnace and these opposite ends are the same, the drawing includes only one of the furnace ends and the two regenerators at this end.

More specifically, the furnace heating chamber 25 connects by way of gas and air ports 2 and 3, up-and-down-takes 4 and 5 and gas and air flues 6 and 7, with gas and air regenerators 8 and 9. The flues 6 and 7 extend over the tops of the regenerators while flues 10 and 11 lead from their bottoms to the usual stack.

Both the flues 10 and 11 are suitably valved to provide the control necessary for reversing the furnace. The details of this are not described because the present invention is particularly concerned with the flows of the products of combustion through the two regenerators to the stack rather than with the reverse flows of gas and air to the furnace, the problem of effecting uniform flows through regenerators being more serious 40 when the regenerators are handling the products of combustion.

The regenerators 8 and 9 are featured by the fact that they converge toward the up-and-down-takes 4 and 5 which are necessarily closely arranged because the gas and air must be injected into a localized portion of the furnace. The flues also converge practically straight from the regenerators to the up-and-down-takes. It follows that the products of combustion exhausting from the furnace by way of the up-and-down-takes are guided into flows which are substantially aligned centrally with the regenerators and therefore pass more uniformly through the latter. The flue 6 is commonly aligned with the 50 regenerator 8, and by inclining the regenerator

9 respecting the latter the flue 7 is much more nearly in alignment with the regenerator 9 than has heretofore been possible. Other arrangements effecting the described converging relationship of the regenerators will effect the same 5 results in varying degrees.

A further feature is that the flue 7, which extends over the top of the regenerator 9, declines toward the stack end of the regenerator whereby to define a space which decreases in cross-sectional area in this direction. Preferably, the declination should be arranged so that the top of the flue almost closes the last row of passages at the stack end of the regenerator. To prevent the products of combustion being carried past the 15 regenerator passages at and near the furnace end, one or more downwardly angling steps 12 are formed in the flue top at spaced positions over the top of this end of the regenerator. These tend to deflect the gaseous flow downwardly at 20 points where its velocity might otherwise carry it past these regenerator passages.

It is necessary to make the various flues from bricks and so their tops are arched to facilitate their construction. It follows that normally the 25 height of the flues extending over the regenerator tops is not transversely uniform but is greatest along the longitudinal center of the regenerator, whereby there is a tendency towards centrally concentrated flows. This undesirable 30 effect is to a large extent eliminated by shaping the top of the regenerator to more nearly conform with the arched flue top, as is illustrated at 9a in Figure 4. With this arrangement the flue 7 has a substantially uniform height transversely of the 35 regenerator top throughout the length of the latter. It may sometimes prove desirable to produce this effect for only a part of the regenerator length.

The features under discussion are illustrated in 40 connection with the air regenerator only, but it is to be understood that they may be advantageously applied to the gas regenerator as well. Furthermore, the bottom of the flue 11 beneath the regenerator 9, and also, if desired, the bottom of the flue 10 beneath the regenerator 8, is provided with upwardly inclined steps 13 which function like the steps 12 when the regenerator is 45 operating reversely.

Although a specific example of the invention 50 is disclosed in accordance with the patent statutes, it is not intended to thereby limit its scope, except to the extents defined by the appended claims.

I claim:

1. A regenerative furnace including an up-and-down-take means, regenerators converging toward said means and flues substantially aligned with said regenerators and extending substantially straight to said means, said flues extending over the tops of said regenerators, and the top of at least one of said regenerators and the flue associated therewith being shaped to provide a space of substantially uniform height transversely of the last named regenerator.
- 5 2. A regenerative furnace including an up-and-down-take means, regenerators converging toward said means and flues substantially aligned with said regenerators and extending substantially straight to said means, said flues extending over the tops of said regenerators, and the top of at least one of said regenerators and the flue associated therewith being shaped to provide a space of substantially uniform height transversely of the last named regenerator which decreases 10 longitudinally toward the remote end of the latter.
- 15 3. A regenerative furnace including an up-and-down-take means, regenerators converging toward said means and flues substantially aligned with said regenerators and extending substantially straight to said means, said flues extending over the tops of said regenerators, and the top of at least one of said regenerators and the flue associated therewith being shaped to provide a space of substantially uniform height transversely 20 of the last named regenerator which decreases longitudinally toward the remote end of the latter, said flue associated therewith providing at 25
- 10 4. A regenerative furnace including an up-and-down-take means, regenerators converging toward said means and flues substantially aligned with said regenerators and extending substantially straight toward said means, said flues extending over the tops of said regenerators, the top of at least one of said regenerators and the flue associated therewith being transversely uneven 15 in shape in such a manner that a rise in said regenerator top is beneath a rise in said flue, said unevenness of said regenerator top being of such an extent as to appreciably reduce the cross-sectional area of said flue at least at 20 the remote end of said regenerator.
- 25 5. A regenerative furnace including an up-and-down-take means, regenerators converging toward said means and flues substantially aligned with said regenerators and extending substantially straight toward said means, said flues extending over the tops of said regenerators, the top of at least one of said regenerators and the flue associated therewith being transversely uneven 30 in shape in such a manner that a rise in said regenerator top is beneath a rise in said flue, said unevenness of said regenerator top being of such an extent as to appreciably reduce the cross-sectional area of said flue at least at 30 the remote end of said regenerator, the cross-sectional area of said flue decreasing gradually toward the remote end of said regenerator.

WILLIAM J. IRWIN.
